GARFIELD P. SMITH, OF BROOKLYN, NEW YORK

GAS ENGINE MUFFLER AND SUPERCHARGER

Application filed February 6, 1930. Serial No. 427,915.

This invention relates to improvements in internal combustion engines, and has more particular relation to muffling and charging devices for such engines.

5 The invention consists in utilizing the power of the engine for assisting in the exhaust and further utilizing the heat of the exhaust and the power of the engine for accentuating or forcing the fresh charge 10 into the engine.

One of the principal objects of the invention is to utilize the heat of the exhaust to heat the inwardly flowing air to the carburetor, and to further utilize the power of 15 the engine for creating a vacuum for more completely exhausting the engine and at the same time putting the pressure on the inwardly flowing air for the carburetor.

A further object of the invention is to 20 provide improved means, operated by the engine, for forcing the charge of air to the carburetor and at the same time have this inwardly flowing air heated by the exhaust gases without mingling with them.

25 A further object of the invention is to provide an "out-board" internal combustion engine, in which a vacuum is applied to the exhaust and in which the charge for the carburetor receives an impulse from the engine, and is heated by the exhaust gases.

The invention also has other objects, all 30 of which will be hereinafter more particularly set forth and claimed.

In the accompanying drawing, Figure 1 35 represents a central vertical section through the devices embodying my invention, partly broken away, and applied to the transom of a boat to be driven thereby.

Figure 2 represents a detail horizontal 40 section of my improved exhaust devices and carburetor charger, taken on the broken levels indicated by the lines 2-2 in Figure 1.

45 Described in general terms, this invention utilizes the power of an internal combustion engine, whether it be of the out-board motor

type or any other type; for operating a centrifugal vacuum-producing wheel connected to the exhaust pipe, and a centrifugal pressure-producing wheel connected to the intake for the carburetor; the two centrifugal 50 wheels being arranged in juxtaposition with a thin dividing wall of metal whereby the heat of the exhaust in one chamber is communicated to and heats the air in the adjoining chamber, so that the air passing to the carburetor will not only be under pressure 55 but will be heated to the desired degree for providing the proper vaporization of the liquid fuel in the carburetor and intake manifolds.

60 Described in detail, 1 represents the transom of the boat upon which my improved engine is mounted.

The engine proper is of any improved 65 type, but for the sake of illustration I have shown an engine of the two-cycle type in diagrammatic arrangement, supported in the usual manner by an adjustable clamp 2. This engine is provided with the usual flywheel 3 and gas tank 4. The crank shaft 5 is extended above the flywheel 3 and supports a hub portion 6 which rests upon the top of the flywheel. A bearing ring 7 surrounds the lower part of the hub 6, and engages a bearing flange 8. A second hub 9 is fast to the projecting end of the crank shaft and is formed with a horizontal partition 10 and top and bottom disks 11 and 12. The hub 9 is further provided with annular vertical walls 13 and 14 apertured as at 15 and 16 to form channels whereby the exhaust gases in the one case and the incoming fresh air in the other case are permitted 75 to enter the two chambers located between the top and bottom plates 11 and 12 and the partition plate 10.

80 The lower edge of the wall 14 is set rigidly in the hub 6 and is formed with ports 17 whereby the exhaust gases may pass therethrough. The ring 7 is supported by a 85 90

casting 18 secured to the top of the fuel tank. The exhaust pipe 19 which communicates with the exhaust port of the engine opens into the chamber formed by the ring 5 7 so that the exhaust gases will pass upward through the ports 17 and will enter the vacuum-producing chamber through the ports 16.

The lower plate or disk 12 rests upon the 10 top of the ring 7 and the inner lower edge of this ring bears against the flange 8. The top plate 11 is formed with an annular enlargement 20 which bears against an annular flange 21 formed on the top plate 22 of the 15 stationary casing 23. The top of the plate 22 near its center is formed with air ports 24 through which air passes into and through the ports 15.

Both the vacuum-producing chamber and 20 the carburetor pressure chamber are provided with vertical partitions or blades 25 and 26 which are joined in each instance to the central annular hub portion in such manner, that when the blades are rotating 25 because of their connection with the hub 9, plates 11 and 12, and partition 10, will rapidly force the air lying between them outward by centrifugal force.

The air entering through the ports 24 30 and being forced outward by the upper blades, will enter a carburetor feed pipe 27 after first being heated by contact with the partition plate 10. So that there will be no leakage between the periphery of the plate 35 10 and the case 22, I provide the interior of the vertical wall of the case with an annular flange 28 against which the periphery of the partition 10 finds a bearing, thus forming two distinct chambers, the lower 40 chamber for the exhaust gases and the upper chamber for the fresh air being fed to the carburetor.

By reference to Figure 1 it will be seen 45 that the lubrication of the contacting surfaces between the casing 22 and the rotor within it, are effected by an oil feeding cup 30 and pipes 31 and 32, which feed oil ducts formed respectively in the casing 22 and in the stationary ring 7.

The oil collecting on the top plate 11 will 50 be thrown outward by centrifugal force, and will drop onto the flange 28 and lubricate the bearing at this point.

The two hubs 6 and 9 are suitably keyed 55 or staked to the extended end of the crank shaft 5, so that the rotor formed by the plates 11, 12, and 10, will move with the crank shaft at all times.

The pipe 27 which leads to the air intake 60 of the carburetor 33 is provided with a butterfly valve 34 which may be adjusted at will to increase or decrease the pressure and temperature of the air flowing inward 65 through the pipe 27 by permitting the en-

trance of air through a screen port 35, or blocking such entrance.

It will be seen that the air rushing through the pipe 27 under pressure from the supercharger will normally hold the 70 valve 34 closed. As the present devices are intended for use, however, on high speed engines and as the tendency of the gases in the intake manifold to lag is quite pronounced at high speed, the supercharger at times cannot keep up with the demands of the engine and a slight vacuum is created in the manifold. When such a vacuum takes place, it is usually of momentary duration as the two cycle type of gas engine inspirates very 75 suddenly when the piston uncovers the inlet port. At such times the valve 34 opens slightly to relieve the vacuum and closes again just as soon as the pressure in the pipe 27 rises. This action prevents starving of 80 the engine or too greatly enriching the mixture at high speed.

The manifold into which the carburetor 33 discharges, is connected in the usual manner to the crank case of the two-cycle engine, while the pipe 19 is connected by a pipe 36, shown in dotted lines in Figure 1, to the exhaust port of the engine.

The operation of the devices is as follows:

Each time the exhaust port of the engine 90 is opened, the gases under pressure pass through the pipe 19 through the port 17 and ports 16 into the lower or vacuum-producing chamber of the rotor. The rapid movement of this rotor in the meantime, together with the centrifugal force exerted by the blades 26 has caused a partial vacuum to be formed in the lower chamber between the plates 10 and 11, and the exhaust gases are thus split up and their pressure greatly reduced, so 100 that the back-pressure on the engine is greatly reduced and its power thus increased. The outwardly flowing exhaust gases pass from the lower chamber through ports 37 105 formed in the rear portion of the vertical wall 23 or through the open bottom at the edge of the lower chamber.

These exhaust gases, in passing through the lower chamber, thoroughly heat the plate 10 so that the fresh air which is passing through the upper chamber becomes heated. As the vanes or blades 25 of the upper chamber are being rapidly moved, the flow of air by centrifugal force is outward from the upper chamber through the carburetor intake manifold 27, the air entering through the apertures 24 at the top of the casing and the ports 15.

It will be observed that while the lower exhaust chamber produces a partial vacuum to more efficiently scavenge the exhaust gases, the upper chamber produces a pressure of heated air which in effect forms a supercharger for the carburetor.

For the above reason I do not care to limit 130

the use of my devices to outboard engines or automobile engines, as the supercharging feature is particularly useful in airplane practice where the elevation of the plane so far reduces atmospheric pressure that some supercharging or pressure of the fuelizing devices becomes necessary.

What I claim is:

1. Combined supercharger and exhaust expeller for internal combustion engines comprising a rotor having a hub adapted to be fixed to the crank shaft of the internal combustion engine, and having parallel circular flanges extending from said hub perpendicular to the axis thereof, forming inner and outer walls and an intermediate partition, radial vanes between said partition and said inner and outer walls defining series of chambers on opposite sides of said partition opening peripherally, a fixed casing overlying said rotor having a peripheral flange encompassing in spaced relation the open ends of said chambers, and having an inner circumferential rib substantially contacting the edge of said partition to segregate the chambers on one side thereof from the chambers on the other side, a fixed ring having an internal circumferential channel journally supported on said hub adjacent the inner wall, said hub being provided with passages, certain of which communicate with the chambers on one side of said partition and with the atmosphere through perforations in said outer wall, and others of which communicate with the chambers on the other side of said partition and with said channeled ring, a conduit adapting the part of said casing above said partition for connection to the carburetor of the engine, and a conduit adapting said ring for connection to the engine exhaust.
2. Combined supercharger and exhaust expeller as claimed in claim 1, the hub being in two parts, the upper part being unitary with the rotor and the lower part providing a seat for the said ring.
3. Combined supercharger and exhaust expeller for internal combustion engines comprising a unitary rotor adapted to be secured to the crank shaft of the engine and having inner and outer series of radially disposed chambers separated by a heat conductive partition, a fixed casing for connection with a carburetor and contacting one end of said rotor and encompassing the sides thereof in spaced relation to said chambers by contacting said partition to segregate said series of chambers, that part of the casing communicating with the lower series of chambers being open to atmosphere adjacent the periphery of said rotor, an air inlet, the upper series of chambers communicating centrally with the air inlet and the lower series of chambers being adapted to communi-

cate centrally with the exhaust of the internal combustion engine.

4. Combined supercharger and exhaust expeller as claimed in claim 3, the casing having an interior annular flange bearing against a circular extension on said rotor, the upper series of chambers communicating with atmosphere by way of perforations formed in said casing within the circumference of engagement between said interior flange and said extension.

In testimony whereof I affix my signature.
